UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

GARMENT SUPPORTER.

Original application filed October 2, 1923, Serial No. 666,074. Divided and this application filed April 2, 1924, Serial No. 703,596.

To all whom it may concern:

Be it known that I, CARL J. HAZELTON, a citizen of the United States, and a resident of Worcester, in the county of Worcester 5 and State of Massachusetts, have invented certain new and useful Improvements in Garment Supporters, of which the following is a specification.

My invention is directed to an improvement in garment supporters and one of the 10 objects thereof is the provision of an improved form of button or stud to be employed in connection with such articles.

Another object of the invention is the provision of an improved garment supporter 15 in which the button is of an improved form facilitating the manufacture of the supporter, particularly the step of assembling, and eliminating certain more or less objectionable characteristics inherent in garment supporters as now constructed.

In garment supporters it is desirable that 20 a fairly long gripping surface be provided for gripping the garment so that the strain on the garment is extended over a considerable area, thereby eliminating danger of tearing or otherwise mutilating the garment. In the present construction I provide a structure wherein the shank of the button 25 is provided with straight parallel sides which are adapted to co-operate with the straight parallel side arms of the holding loop and, as will be hereinafter pointed out, by this construction I am enabled to provide a long gripping surface between the 30 side arms of the holding loop and the side faces of the shank of the button, which extended gripping surface affords the advantages above referred to as being desirable 35 in garment supporters.

In the manufacture of garment supporters ease of assembling is desirable. In this connection I may here note that I have provided a supporter in which the button and 40 base-plate constituting a part of the supporter structure may be rapidly assembled, the front and rear faces of the shank being curved so that no great care need be taken in assembling these two parts of the supporter. In other words, this type of supporter is different from that shown in my co-pending application, Serial No. 641,614, 45 for example, wherein a segmental shank is provided, the straight portion of the seg-

ment constituting the front face of the button shank. In such a construction it will be apparent that care must be exercised in assembling the button and base-plate in order to insure that the straight face of the segmental shank will be positioned at the 55 lower end of the supporter.

In the accompanying drawings—

Figure 1 shows my improved supporter in front elevation,

Fig. 2 is a section taken through the shank 65 of the button showing the base-plate and button removed from the rest of the garment supporter; and

Fig. 3 is a section taken on the line 3—3 of Fig. 1. 70

Referring to the drawings in detail, 29 designates a base-plate which is attached to a tab 30, openings 30' being provided in the base-plate for the reception of this tab.

Mounted on or attached to this base-plate 75 is a button or stud comprising a head 31, which in the present instance is elongated, being oval shaped, the long axis of the head extending transversely of the supporter. This button is provided with a shank 32. It 80 will be understood, of course, that the shank and the head of the button are integral with each other, and I may here mention that a button of this character is usually constructed of rubber. The shank 32 is provided with 85 relatively long, straight, parallel sides 33, the shank being so disposed relatively to the head of the button that these straight sides or faces extend transversely of the long axis of the button head and longitudinally of 90 the supporter. The shank 32 is also provided with a curved front face or surface 34 and a similarly curved rear face 35. The head of the button projects beyond the shank throughout the periphery of the shank, 95 thereby providing an annular peripheral flange or overhang.

The holding loop, which is adapted to co-operate with the button just described, is 100 designated 36 and is provided with substantially straight, parallel side arms 37 and a curved cross-bar 38, this cross-bar being located at the lower extremity of the side arms 37 and its curvature conforming to the curve of the front and back faces 34 and 35 105 of the button shank.

The button is attached to the base-plate 29 by means of a holding rivet, designated

40. This holding rivet or stud passes entirely through the button,—that is to say, through the head and shank of the button,—and into the base-plate 29 and is provided with an elongated head adapted to lie in and co-operate with a groove 39 in the upper face of the button head. The groove 39, which as above noted is elongated, extends lengthwise of the button and transversely of the button shank and is long enough to project beyond the sides of the shank and to overhang the side arms 37 of the holding loop.

In operation it will be apparent that a garment to be supported will be pinched or gripped between the side arms 37 of the holding loop and the relatively long, straight sides 33 of the button shank, as well as between the curved cross-bar 38 and the curved front face 34 of the button shank. It will be apparent also that by providing an overhang or a flange overhanging the shank of the button throughout its periphery, the cross-bar 38 will overlie a flange on the head of the button whether the button be positioned as indicated in Fig. 1 or rotated through 180 degrees from that position. In other words, no care need be taken in assembling the button and base-plate so far as the curved faces of the shank are concerned, which is of material advantage so far as assembling is concerned as compared with the buttons of the type illustrated in my co-pending application above referred to.

35. This application is a division of my co-pending application, Serial No. 666,074, filed October 2, 1923.

What I claim is:

1. A button comprising an elongated head and a shank, said shank having relatively long, straight sides or side faces and curved front and rear faces, said head extending beyond the shank throughout the periphery of the shank, and the long axis of the shank 45 extending transversely of the long axis of the button head.

2. In combination a base-plate, a button attached to said base-plate, said button comprising a head and a shank, said shank having curved faces front and back and straight, parallel side faces, and attaching means passing through said button head and shank and into said base-plate for attaching

the button to the base-plate, said attaching means being provided with a head extending beyond the straight sides of the shank. 55

3. In combination a base-plate, a button attached to said base-plate, said button comprising a head and a shank, said shank having curved faces front and back, and attaching means passing through said button head and shank and into said base-plate for attaching the button to the base-plate, the head of said button extending beyond the curved faces of the shank, and the head of 65 the securing means extending beyond the sides of the shank.

4. In combination a base-plate, a button attached thereto and comprising a head and a shank, said shank having curved faces 70 front and back and straight opposed side faces, and attaching means passing through said head and shank and into said base-plate for attaching the button to the base-plate, the head of said button overhanging said 75 shank throughout its periphery and the head of said attaching means extending beyond the straight opposed side faces of the shank.

5. In combination a base-plate, a button 80 attached thereto and comprising a shank having curved front and rear faces and straight sides, an elongated head for the button, the long axis of which is transverse of the long sides of the shank, and means 85 passing through said button head and shank for attaching the button to the base-plate, said attaching means having an elongated head extending lengthwise of the button head and overhanging the straight sides of 90 the shank.

6. In combination a hose supporter loop having straight, parallel side arms and a curved cross-bar at the extremity of said arms, a button comprising a head and a shank, said button head being elongated and extending transversely of the loop, a shank for said button having straight, parallel side faces co-operating with the side arms of the loop, said straight faces extending parallel to said side arms and transverse of the button head. 95 100

This specification signed this 31st day of March, 1924.

CARL J. HAZELTON.
